UNITED STATES PATENT OFFICE.

JOHN CLAYTON BACKUS, OF SMETHPORT, PENNSYLVANIA, ASSIGNOR TO BACKUS NOVELTY COMPANY, OF SMETHPORT, PENNSYLVANIA, A CORPORATION OF WEST VIRGINIA.

ASH TRAY.

Application filed March 22, 1922. Serial No. 545,776.

To all whom it may concern:

Be it known that I, JOHN CLAYTON BACKUS, a citizen of the United States, residing at Smethport, in the county of McKean and State of Pennsylvania, have invented certain new and useful Improvements in Ash Trays, of which the following is a specification.

This invention relates to an improved ash tray particularly designed for use in automobiles of the closed type such, for instance, as a limousine or sedan, and seeks, as one of its principal objects, to provide a device which may be readily attached to the upholstery of such a vehicle.

The invention has as a further object to provide a device employing a supporting bracket and wherein the bracket may be pressed from suitable sheet metal.

And the invention has as a still further object to provide a device wherein the receptacle employed will be detachably mounted upon the bracket and wherein a spring will be provided for frictionally holding the receptacle upon the bracket so that the receptacle may be readily applied or removed.

Other and incidental objects will appear hereinafter.

In the drawing:

Figure 1 is a fragmentary perspective view showing the manner in which my improved ash tray may be mounted within a motor vehicle.

Figure 2 is a perspective view showing the receptacle removed from the supporting bracket of the tray.

Figure 3 is a vertical sectional view through the device, and

Figure 4 is a fragmentary perspective view of the supporting bracket.

In carrying the invention into effect, I employ a supporting bracket comprising an annular top plate 10 from which extends, at substantially right angles, a base plate 11. As shown in the drawing, the bracket is preferably constructed from a single piece of suitable resilient sheet metal and depending from the top plate is a split annular rim or flange 12 provided at its ends with laterally deflected lugs 13 which are bent to abut the inner face of the base plate 11. These lugs thus lie in the angle between the base plate and top plate of the bracket and are widened to coact with the base plate

for rigidly supporting the top plate with respect to the base plate. As best brought out in Figures 2 and 3, the top plate is provided with a central opening 14 and is pressed downwardly to provide a conical wall 15 sloping toward said opening. Mounted upon the base plate 11 near its upper end is a double-ended attaching member 16. This member is preferably formed from a length of suitable resilient wire and comprises spaced parallel prongs 17 joined by an intermediate connecting portion which, as shown in Figure 4, lies flat against the inner face of the plate while the prongs are arranged to extend through suitable openings in the plate to depend in spaced parallel relation at the rear face of the plate. Rigidly securing the member in position is a bond of solder 18. The base plate is preferably tapered toward its lower end and is provided with openings 19 therein so that should it be so desired, the bracket may be permanently mounted by screws engaged through said openings. The prongs 17 terminate at their free extremities substantially half way between the ends of the base plate and mounted upon said plate at its forward side is a medially disposed flat spring 20. This spring is riveted or otherwise secured at its lower end to the base plate and is offset to extend at its free upper end in spaced parallel relation to said plate.

In conjunction with the supporting bracket, I employ a cylindrical receptacle 21. As shown in Figure 2, the wall of said receptacle is pressed outwardly or offset near its upper edge to provide a spacing ring 22 at the mouth of the receptacle and, as brought out in Figure 3, said ring is adapted to snugly fit within the flange 12 of the top plate 10 of the supporting bracket of the device frictionally coacting with the spring 20, the spring being held under tension by the ring for locking the receptacle upon the bracket. However, the receptacle may, of course, be readily removed by pulling downwardly thereon and may be replaced with equal facility so that the receptacle may be conveniently emptied at any time. As will be noted, the top plate will provide a cover for the receptacle while the sloping wall 15 of said plate will serve to direct ashes deposited thereon into the receptacle.

As previously intimated, my improved ash tray is particularly designed for use in

connection with closed automobiles and I have accordingly, in Figure 1 of the drawing, shown the device upon the door 23 of such a vehicle. As will be observed, the 5 prongs 17 are engaged in the upholstery of the door for connecting the supporting bracket therewith so that the base plate 11 will thus be disposed to sustain the top plate 10 extending at right angles to the inner 10 face of the door. Thus, the device may be readily secured in position without likelihood of injury to the upholstery while the receptacle will be supported in a position 15 convenient for use.

15 Having thus described the invention, what is claimed as new is:

1. In an ash tray, the combination of a supporting bracket having a top plate, a receptacle fitting the top plate and removable 20 downwardly at the lower side thereof, and yieldable means frictionally locking the receptacle upon the bracket.
2. In an ash tray, the combination of a supporting bracket having a top plate provided with a depending flange, a receptacle fitting in said flange and removable 25 downwardly at the lower side of said plate, and yieldable means frictionally locking the receptacle upon the bracket sustaining a portion of the weight of the receptacle.

3. In an ash tray, the combination of a supporting bracket having a top plate, a receptacle fitting said plate and removable 30 downwardly at the lower side thereof, and yieldable means mounted upon the bracket below said plate to engage the receptacle frictionally locking the receptacle upon the bracket.

4. In an ash tray, the combination of a supporting bracket having a top plate, a receptacle fitting the top plate and removable 40 downwardly at the lower side thereof, and a spring mounted at one end upon the bracket below said plate to coact at its free end with the receptacle locking the receptacle upon the bracket. 45

5. In an ash tray, the combination of a supporting bracket having a top plate, a receptacle fitting the top plate partially closed thereby and removable downwardly at the 50 lower side of the plate, and yieldable means frictionally locking the receptacle upon the bracket sustaining a portion of the weight of the receptacle.

6. In an ash tray, the combination of a supporting bracket having a base plate provided with an angularly disposed top plate, the top plate being formed with a depending flange coacting between said plates bracing the top plate with respect to the base plate, a receptacle fitting in said flange and removable 60 downwardly at the lower side of said plate, and means removably locking the receptacle upon the bracket.

7. In an ash tray, the combination of a supporting bracket including a base plate having a top plate extending therefrom and provided with a depending split flange formed at its ends with lugs abutting the base plate for bracing the top plate with respect to the base plate, an attaching device carried by the bracket, a receptacle fitting in said flange, and means removably locking the receptacle upon the bracket. 65

In testimony whereof I affix my signature,
JOHN CLAYTON BACKUS. [L. s.] 70
